US00D748506S

(12) **United States Design Patent**
Stecker et al.

(10) **Patent No.:** US D748,506 S
(45) **Date of Patent:** ** Feb. 2, 2016

(54) **SENSOR**

- (71) Applicant: **Banner Engineering Corporation**, Minneapolis, MN (US)
- (72) Inventors: **John Alyn Stecker**, Maple Lake, MN (US); **Matthew Alexander Payne**, Columbia Heights, MN (US)
- (73) Assignee: **Banner Engineering Corporation**, Minneapolis, MN (US)
- (**) Term: **14 Years**
- (21) Appl. No.: **29/502,422**
- (22) Filed: **Sep. 16, 2014**

(57) **CLAIM**

The ornamental design for a sensor, as shown and described.

DESCRIPTION

FIG. 1 is a perspective rear/top/right view of a sensor according to one aspect of the present disclosure;
FIG. 2 is a back view of the sensor depicted in FIG. 1;
FIG. 3 is a front view of the sensor depicted in FIG. 1;
FIG. 4 is a right view of the sensor depicted in FIG. 1;
FIG. 5 is a left view of the sensor depicted in FIG. 1;
FIG. 6 is a top view of the sensor depicted in FIG. 1;
FIG. 7 is a bottom view of the sensor depicted in FIG. 1;
FIG. 8 is a perspective front/top/left view of the sensor depicted in FIG. 1;
FIG. 9 is a perspective rear/top/left view of the sensor depicted in FIG. 1; and,
FIG. 10 is a rear/top view of the sensor depicted in FIG. 1. The broken-line showing of structural features is included for the purpose of illustrating non-claimed subject matter and forms no part of the claimed design.
